UNITED STATES PATENT OFFICE.

SAMUEL H. FETTER, OF SUNBURY, PENNSYLVANIA, ASSIGNOR OF ONE-HALF TO
TRUMAN J. PURDY, OF SUNBURY, PENNSYLVANIA.

ROAD-REPAIRING APPARATUS.

Application filed August 27, 1923. Serial No. 659,553.

To all whom it may concern:

Be it known that I, SAMUEL H. FETTER, a citizen of the United States, residing at Sunbury, in the county of Northumberland and State of Pennsylvania, have invented 5 certain new and useful Improvements in Road-Repairing Apparatus; and I do hereby declare the following to be a full, clear, and exact description of the invention, such 10 as will enable others skilled in the art to which it appertains to make and use the same.

The invention relates to apparatus for repairing damaged road surfaces and structures by the application of a repair medium such as asphalt, bitumen and the like, by means of a special form of heating and smoothing device, associated with a receptacle to contain the repairing medium, which latter is preferably delivered through a discharge orifice in the smoothing device, in regulated quantities to fill up the cracks, abrasions or other cavities formed in the surface and body of the road structure, and 25 to effect a thorough union between the filling material and the road structure, by the application of heat and pressure from the smoothing device. Preferably the device is associated with a vehicle carried unit, 30 comprising a dynamo electric generator driven by an internal combustion motor, a tank for holding the repairing material, which tank is preferably heated by the exhaust gases from the internal combustion motor, by an electric heater supplied with 35 current from the generator; or by both, said generator also supplying current to heat the smoothing device and also the material carried by the receptacle associated therewith, and preferably to supply current to a heating coil associated with or incorporated in the body of a hose or flexible conduit connecting the tank with the receptacle on the smoothing device so that the repair material 40 may be maintained at the proper temperature to cause the same to flow readily and also to coalesce with and form an intimate union with the road structure to be repaired.

50 The invention is illustrated in the accompanying drawing, in which

Fig. 1 is a side elevation of the apparatus associated with an automobile truck.

Fig. 2 is a plan view.

55 Fig. 3 is a longitudinal sectional elevation

of the smoothing device and the associated receptacle for the repair material.

Fig. 4 is a sectional elevation of the storage tank.

Fig. 5 is a detail view, partly in section, 60 of the discharge pipe from the tank and the flexible hose.

Fig. 6 is a plan view of the smoothing device graphically illustrating the electric heating unit therein. 65

Fig. 7 is a detail view of the regulable supporting means for the smoothing device.

Fig. 8 is a diagram of the circuits.

Referring to the drawing, 1 indicates an automobile truck of any suitable type, upon 70 the rear of which is removably mounted a skid or framework 2 carrying a storage tank 3 provided with a heating jacket 4, and an internal combustion engine 5, the exhaust 6 of which discharges into the heating jacket 75 4 of the tank 3, finally escaping from the exhaust pipe 7 preferably located near the top of the tank.

The internal combustion motor 5 is connected in any suitable manner to a dynamo 80 electric generator 8. The tank 3 is provided with a discharge pipe 10, at its lower rear portion, which pipe is provided with a regulating valve 11. The unit 6 thus described is designed to provide a reserve supply of the repair material, such as asphalt, 85 bitumen or the like in the tank, which material is maintained in a properly heated condition either by means of the exhaust gases from the internal combustion motor, 90 by means of an electric heating unit supplied with current from the generator, or by both of said heating means.

The repair material is supplied to the road surfaces to fill up the cracks, abrasions or 95 other cavities in the road surface or structure by means of a novel form of smoothing device or iron, the principal elements of which are a relatively heavy body portion 15 upon the top of which is mounted a receptacle 20 to receive the bitumen or asphalt which constitutes the repair medium. The body portion 15 preferably consists of a generally rectangular block or casting of iron, of appropriate weight to develop a maximum pressure on the road surface of substantially fifty pounds, which, as a general rule, will be sufficient to force the hot repair medium into all of the cracks and other 100 openings in the road surface or structure, 105 110

effect an intimate union between the repair material and the body of the road and also to smooth out all irregularities in the repaired sections of the road. The receptacle 20 is provided with an inlet 22 and also a larger opening 21, provided with a removable cover 21'. The opening 22 is adapted to be connected by means of a hose or similar flexible conduit 23 with the discharge 10 pipe 10 of the tank 3, when the smoothing device is employed in conjunction with the tank and its accessories carried by the automobile truck. The covered opening 21 is to be used for filling the receptacle when 15 the smoothing device is used independently of the truck, and also for the purpose of cleaning out the receptacle when such operation is found necessary.

The body portion 15 of the smoothing 20 device is provided with a vertical discharge orifice 17 opening into the lower or smoothing face 16 of the body, which latter is normally in contact with the road surface during the application of the repair material to 25 the road. The discharge orifice is controlled by a suitable valve which may take the form of a sliding gate 18 which is operated in a slot formed in said body portion, said gate being controlled by a handle 19, the 30 outer end of which is supported from a suitable handle or draft bar 20', by means of which the smoothing device is moved and directed over the particular portion of the road surface to which the repair material is 35 to be delivered.

As indicated, the smoothing device is adapted to be connected to the tank 3 by means of a flexible hose 23, of suitable length to permit a wide range of operation 40 of the smoothing device with respect to the automobile vehicle upon which the supply tank 3 is carried.

In order to regulate the pressure applied by the iron or smoothing device to the road 45 surface, during the application of the repair material, the said device is provided with adjustable castors or rollers, which may conveniently take the form illustrated in Fig. 7, in which 24 indicates the wheel of 50 one of four such rollers or castors, disposed in pairs on opposite sides of the smoothing device, said roller being mounted in a yoke 25, slidably mounted in a socket 26, which latter is adjustably secured to the side of the 55 smoothing device by means of bolts 29 passing through slots 28 in the plate 27. Preferably each of the rollers is cushioned by a spring 30 mounted in the socket 26, the tension of which spring is regulated by a 60 set screw and follower 31 threaded into the top of the socket. By adjusting the foot plates 27 on the sockets 26 up or down, it will be apparent that the amount of pressure or dead weight of the smoothing device directed 65 to the road surface may be accurately

regulated and any desired portion of the weight of the device may be taken up by the rollers. Also by moving the adjustable sockets downward to the full extent of their 70 adjustments, the smoothing device will be raised entirely out of contact with the road surface and will be supported wholly by the rollers or castors to facilitate transportation of the smoothing device when the latter is not in operation.

Inasmuch as the repair material is applied to the road intermittently and in relatively small quantities, it is necessary to maintain the temperature of the asphalt or bitumen contained in the receptacle 3 at a proper uniform temperature, which may vary from one hundred and fifty to four hundred degrees, depending upon the particular character of the material employed. It is also necessary to heat the smoothing device to a similar degree in order to heat the surface of the road to be treated and to effect a thorough coalescence between the binding medium and the surfaces of the road structure with which the latter comes into contact. This dual heating function is preferably produced by means of an electric heating device, of any convenient or preferred form, which receives its supply of heating current from the generator 8. As shown, the body 15 of the smoothing device has imbedded therein a heating unit 14, which is adapted to be coupled up with the generator 8 by means of suitable leads, in one of which is interposed a rheostat and switching device 42, by means of which the current is switched on and off and the amount of current supplied to the heating device 44 is accurately regulated to maintain the desired temperature of the smoothing body or iron 15 and also to maintain the proper degree of temperature in the repair material contained within the receptacle 20, which latter result will be produced by the heat transmitted from the body 15 directly to the material in the receptacle. Obviously, if desired, the body of the iron or smoothing device 15 may be heated in whole or in part by means of the exhaust gases from the internal combustion motor 5, as by suitably jacketing the body 15 and leading the exhaust gases from the motor through the jacket by means of a suitable flexible conduit, and, if desired, both the electric and exhaust gas heating means may be employed.

It may also be found necessary to supply heat to the repair material as the latter passes from the tank 3 to the receptacle 20 of the smoothing device, in order to maintain the proper temperature of the material. To effect this object, the hose 23 may be jacketed to receive the exhaust gases which pass from the engine 45 through the jacket of the tank 3, in which case the jacket of the hose 23 will be connected to the jacket 125 130

of the body 15 of the iron or smoothing device, so that the exhaust gases will pass continuously from the engine 45 through the jacket of the tank 3, the jacket of the hose 23 and the jacket of the iron 15, from which latter they will be exhausted to the atmosphere. Preferably, however, a special form of electric heating device is provided for the hose 23, which may be used either alone or in conjunction with the exhaust gases from the engine 45. As illustrated in Fig. 5, the flexible hose has imbedded therein or associated therewith an electric heating coil 47, which is connected with the leads from the generator 8, preferably in parallel with the coils of the heating device 44, as shown in the diagram of Fig. 8.

The electric circuits for effecting the heating of the iron 15 and the hose 23 are shown in Fig. 8 as follows: from one brush of the generator 8 through lead 41 to the arm of the switch and rheostat 42, thence by lead 43 to one terminal of the heating coil 44, through said coil and lead 45 back to the other brush of the generator, branches 46 and 48 serve to connect the coil 47 of the heating unit, associated with the hose 23, in parallel with the coil 44 so that the amount of current supplied to the heating units 44 and 47 will be simultaneously regulated by the rheostat 42.

In operating the smoothing unit alone, the receptacle 20 is filled with hot asphalt, bitumen or similar repair material, and the heating unit 44 is connected with a suitable electric supply so that the body 15 of the smoothing device is raised to the appropriate temperature. The amount of pressure to be developed by the smoothing device on the road surface is determined, in accordance with the character of the repair material employed, and the supporting rollers or castors are adjusted so as to take up the excess weight of the smoothing device. When these adjustments have been made and the repair material in the receptacle 20 has been raised to the proper temperature, the machine is moved over the particular portions of the road to be repaired, such as cracks, abrasions or other cavities in the road, and the slide valve is moved to open the discharge orifice 17 connecting the interior of the receptacle 20 with the lower or road engaging surface of the smoothing device or iron 15. The hot repair material flows through the orifice and into the cavities in the road surface and structure, and as the road absorbs heat from the smoothing device, that portion of the road to receive the repair material will be properly heated to effect an intimate coalescence between the repair material and the road structure. The surface of the smoothing device being in intimate contact with the road surface, it will smooth off and reduce all inequalities in the

supplied material and will also, in a large measure, smooth out any existing inequalities in the road surface itself when the latter includes, in its construction, a plastic stitch as asphalt, bitumen, tar or the like. In order that the repair material may be applied only where necessary, the smoothing device is moved and guided by the handle 20' so that the mouth of the discharge orifice 17 will follow the course of the cracks in the roadway or traverse back and forth over larger depressions or cavities which may have been formed in the road surface or structure. By this means, the proper amount of repair material may be accurately distributed and incorporated with the road surface and structure and the road surface smoothed off and compacted in a single operation. In case the device is to be used in the application of hot or cold patches to a road surface, including the use of mineral aggregates, such as crushed stone, gravel or sand, the solid material may be filled into the cavities in the road and brought to the proper grade, after which the smoothing device may be moved back and forth over the surface of the supplied aggregate to distribute a proper quantity of the hot binding medium thereto and effect a thorough compacting of the composite patch and an intimate union between the latter and the body of the road.

When it is desired to use the smoothing device to iron out existing irregularities, such as waves, "shoves" or "rolls" in the surface of a composite road which includes a more or less viscous binding medium in the composition, the smoothing device may be employed without the application of the repair medium, by heating the same to the necessary temperature and then drawing the device over the irregularities in the road surface until the same has been heated and softened sufficiently, so that they will effectively iron out under the pressure imposed by the weight of the body 15 and its accessories.

When the smoothing device is employed in conjunction with the supply unit on the truck, it is coupled with the tank 3 by means of the hose 23 as hereinbefore explained and a sufficient amount of the hot repair material in the tank is supplied to the receptacle 20 by opening up the valve 11. The electric heating units 44 and 47 are connected with the generator 8, and to facilitate this operation, the cable containing the main leads 43 and 45 is wound around the hose 23, the ends of the leads being provided with a suitable coupling which engages the terminals of the heating device 44. After the receptacle 20 has been filled, the valve 11 is closed. The smoothing device is then operated over the particular sections of the road to be repaired, as hereinbefore de-

scribed, until the receptacle is practically exhausted. In moving from one to another of the cracks, or depressions where repairs are to be made, the valve 18 is closed. During 5 the entire operation, the reserve material in the tank 3 is kept at a substantially uniform temperature by the particular heating means described, so that the hot material may be supplied to the receptacle 20 whenever necessary, the temperature being maintained while the material is in transit from the tank to the receptacle by means of the heating unit in the connecting hose. Obviously, two or more of the smoothing devices 10 may be coupled up with the same supply unit on the automobile truck where the exigencies require multiple units but, as a general rule, a single smoothing device will be found sufficient to meet all the requirements of ordinary repair work.

What I claim is:

1. Apparatus for repairing road surfaces comprising a weighted smoothing device, a receptacle for repair material thereon, means for discharging the material in regulable quantities from said receptacle onto portions of the road acted upon by the smoothing device, and means for heating said device.
2. Apparatus for repairing road surfaces comprising a smoothing iron having a valved discharge orifice therein, a receptacle for repair material on said iron and connected with said orifice, means for moving said iron over the surface to be repaired, and means for heating the iron and the material in said receptacle.
3. Apparatus for repairing road surfaces comprising a smoothing iron having a valved discharge orifice in its road engaging surface, a receptacle for receiving repair material on said iron and connected with said orifice, means for moving said iron over the surface to be repaired, and means for heating the iron and the material in said receptacle.
4. Apparatus for repairing road surfaces comprising a weighted smoothing device having a discharge opening in its road engaging surface, means for supplying repair material to the road surface through said orifice, means for heating said smoothing device, and means for moving said device over the surface to be repaired.
5. Apparatus for repairing road surfaces comprising a weighted smoothing device having a discharge opening in its road engaging surface, means for supplying repair material to the road surface through said

orifice, means for heating said smoothing device, means for moving said device over the surface to be repaired, and adjustable supporting means on said device for regulating the pressure of the smoothing surface thereof on the road.

6. Apparatus for repairing road surfaces comprising a weighted smoothing device having a discharge opening in its road engaging surface, means for supplying repair material to the road surface through said orifice, means for heating said smoothing device, means for moving said device over the surface to be repaired, and adjustable supporting wheels on said device for regulating the pressure of the smoothing surface of the latter on the road.

7. Apparatus for repairing road surfaces comprising a portable receptacle for repair material having a weighted bottom constituting a smoothing device provided with a discharge orifice in its lower face for directing the material onto the road surface, means for heating said bottom, and means for moving the device over the surface of the road to be repaired.

8. Apparatus for repairing road surfaces comprising a portable receptacle for repair material having a weighted bottom constituting a smoothing device provided with a discharge orifice in its lower face for directing the material onto the road surface, means for heating said bottom, and a handle for moving the device over the surface of the road to be repaired.

9. Apparatus for repairing road surfaces comprising a smoothing iron having a receptacle for repair material on its back and a discharge orifice connecting said receptacle with the road engaging face of the iron, a storage tank for the repair material, a flexible conduit connecting the tank with the receptacle, means for heating the material in the tank and the smoothing iron, and means for moving the iron over the surface of the road to be repaired.

10. Apparatus for repairing road surfaces comprising a smoothing iron having a receptacle for repair material on its back, a regulating valve controlling said orifice, a storage tank for the repair material, a flexible conduit connecting the tank with the receptacle, means for heating the material in the tank and the smoothing iron, and means for moving the iron over the surface of the road to be repaired.

In testimony whereof I affix my signature.

SAMUEL H. FETTER.
